UNITED STATES PATENT OFFICE

EUGENE HERRING, OF NEW ORLEANS, LOUISIANA, ASSIGNOR TO ELM CITY COTTON MILLS, OF LAGRANGE, GEORGIA, A CORPORATION OF GEORGIA

LOOM

Application filed September 12, 1927. Serial No. 219,065.

This invention aims to provide a loom attachment which is so constructed that a leno weave, open mesh laundry bag may be formed by the vertical and lateral movement of a single harness with respect to a stationary harness.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in elevation, a portion of a loom wherein the device forming the subject matter of this application has been embodied;

Figure 2 is an elevation taken at right angles to the showing of Figure 1;

Figure 3 is a vertical fragmental section illustrating, for the most part in elevation, the means whereby the up and down movement is imparted to the movable harness;

Figure 4 is a diagrammatic view showing the movable harness carried down and to the right, the first pick being indicated;

Figure 5 is a diagrammatic view wherein the movable harness has been carried up and to the right, the second pick being indicated;

Figure 6 is a diagrammatic view wherein the movable harness has been carried down and to the left, the third pick being indicated;

Figure 7 is a diagrammatic view wherein the movable harness has been carried up and to the left, the fourth pick being indicated;

Figure 8 is an elevation showing the fixed harness, parts being broken away;

Figure 9 is a top plan of the fixed and movable harnesses when they are in the positions indicated diagrammatically in Figure 4, parts being in section;

Figure 10 is a plan showing a piece of the leno-woven laundry bag fabric;

Figure 11 is a top plan showing the fixed and movable harnesses in the relative positions wherein they are diagrammatically shown in Figure 6, parts being in section;

Figure 12 is a diagrammatic view illustrating the relative positions of the warp threads on the various picks;

Figure 13 is an elevation of the cam wheel.

The numeral 1 marks a loom frame on which a stationary harness 2 is suspended at 30 42. On one side of the stationary harness 2 is located a movable harness 3, the comb appearing at 4. In order to provide for an up and down movement of the harness 3, the said harness is carried by flexible straps 5 65 rove over pulleys 6 on the frame 1 and connected to a counter-weight 7 located on the opposite side of the harness 2 from the harness 3. The lower edge of the counterweight 7 is united by connections 8 with the forward 70 ends of levers 9, and the lower edge of the harness 3 is connected by flexible straps 10 to the forward ends of levers 11, the levers 9 and 11 being fulcrumed at 12, intermediate their ends, on the frame 1. A main shaft 14 75 is journaled on the frame 1 and is rotated by any suitable means 15, the shaft having eccentrics 16 and 17, the eccentrics 16 co-operating with the rear ends of the levers 11, and the eccentrics 17 co-operating with the 80 rear ends of the levers 9. A bracket 18 forms part of the frame 1, and thereon a counter-shaft 19 is journaled, the shafts 14 and 19 being connected by beveled gears 20. A wheel 21 is secured to the shaft 19 and has a 85 lateral cam track 22 in which moves a projection 23 on a lever 24 fulcrumed intermediate its ends on the bracket 18, the upper end of the lever 24 moving in a guide 29 on the frame 1. A lever 25 is fulcrumed intermediate its ends on the frame 1, a rigid longitudinally-adjustable link 26 being pivotally connected to the upper end of the lever 25, and being pivotally and adjustably connected to the upper end of the lever 24. The lever 25 is provided at its lower end with an eye 27, receiving loosely, a loop-shaped connection 28 on one end of the movable harness 3, the construction being such that the harness moves up and down on the lever 25, the lever 230

25 forming part of the mechanism for moving the harness 3 sidewise, the shaft 14 constituting a single actuator for the means whereby the harness 3 is moved up and down, 5 and for the means whereby the harness is moved sidewise.

The vertical or up and down components in the movement of the harness 3 are derived from a train of elements including the driving means 15, the shaft 14, the eccentrics 16 and 17, the levers 11 and 9, the connections 10 and 8, the counter-weight 7, and the straps 5. The horizontal or sidewise components in the movement of the harness 3 are derived, 15 by way of the shaft 14, from a train of elements including the beveled gears 20, the counter-shaft 19, the wheel 21, its cam track 22, the projection 23, the lever 24, the link 26, the lever 25, the eye 27, and the connection 28 on the end of the harness 3.

The stationary harness 2 has bars 30. Between two adjoining bars 30 is located a depending needle 31 having an eye 32, and between one of the aforesaid bars and the 25 next adjoining bar is located an upstanding needle 33 having an eye 34. The movable harness 3 has bars 35. Between two adjoining bars 35 is located a depending needle 36 having an eye 37, and between one of the aforesaid bars and the next adjoining bar is located an upstanding needle 38 having an eye 39.

The complete fabric is of the tubular form used in the making of open mesh laundry 35 bag, and for convenience, the bag may be said to consist of a top layer and a bottom layer, a portion of one layer being shown in Figure 10 and comprising warp threads *d* and *c* and woof threads *e*. The warp threads *d* and *c* are crossed, as at *f*, between the woof threads 40 *e*. The warp threads of the bottom layer are marked by the letters *a* and *b*, whereas the letters *c* and *d* designate the warp threads of the upper layer.

45 The threads *d* and *c* pass between two dents of the comb 4. The thread *d* extends between two adjacent bars 35 of the movable harness 3 and through the eye 34 of the stationary harness 2. The thread *c* extends through the 50 eye 36 of the movable harness 3 and between two adjacent bars 30 of the stationary harness 2. The threads *a* and *b* pass between two dents of the comb 4. The thread *a* extends between two adjacent bars 35 of the movable harness 3 and through the eye 32 of the stationary harness 2. The thread *b* extends through the 55 eye 37 of the movable harness 3 and between two adjacent bars 30 of the stationary harness 2.

60 Referring to Figure 4, the movable harness 3 has been moved down and to the right. On the first pick, the woof thread *e* is carried over the top of the warp threads *b*, *c*, and *a*, and under the thread *d*. In Figure 5, the 65 movable harness has been moved up and to

the right. On the second pick, the woof thread *e* is carried beneath the warp threads *d*, *c*, and *b*, and over the thread *a*. In Figure 6, the movable harness 3 has been carried down and to the left. On the third pick, the woof thread *e* is carried over the warp threads *a*, *b*, and *c*, and under the thread *d*. In Figure 7, the movable harness has been carried up and to the left. On the fourth pick, the woof thread *e* is carried under the warp threads *d*, *c*, and *b*, and under the thread *a*. At the proper times, considered relatively to the various picks, the threads *c*—*d* and *a*—*b* are crossed on each other at *f*, to form the leno-weave.

Owing to the provision of the mechanism depicted in Figures 1, 2, 3, and 13, of the drawings, a single harness, to wit, the harness 3, moving with respect to the fixed harness 2, will effect the completion of a leno-woven tubular bag, the mechanism being simplified greatly.

For convenience, the levers 9, which move the harness 3 up, may be denominated the first levers, the levers 11, which move the harness down, being designated as the second levers, the lever 25 of Figure 1 being the third lever, and the lever 24 being the fourth lever.

What is claimed is:—

1. In a loom of the class described, a frame, a harness, means for mounting the harness on the frame for up and down movement and for sidewise movement, a shaft journaled on the frame, means operated by the shaft and connected to the harness for moving the harness up and down, third and fourth levers mounted on the frame to swing sidewise in approximate parallelism to the shaft, the harness being slidable on the third lever, a link connecting the third and fourth levers, a cam wheel operatively connected with the fourth lever and disposed in approximate parallelism to the shaft, and means for connecting the cam wheel operatively with the shaft.

2. In a two-harness leno-weave loom for making mesh bags, the combination of a frame, a comb mounted upon the frame, two harnesses having oppositely projecting needles, one harness being stationary on the frame, the other harness being movable and being located between the comb and the fixed harness, means for mounting the movable harness for up and down movement and for lateral movement with respect to the comb and the stationary harness, and mechanism for moving the movable harness as aforesaid, to effect a leno-weave.

In testimony that I claim the foregoing as my own, I have hereto affixed my signature.

EUGENE HERRING.
